Patented Feb. 20, 1917.

2 SHEETS—SHEET 2.

UNITED STATES PATENT OFFICE.

LEGENDRE CINQ-MARS, OF SAN FRANCISCO, CALIFORNIA, ASSIGNOR TO CONSERVATIVE
HEATING COMPANY, OF SAN FRANCISCO, CALIFORNIA, A CORPORATION.

ELECTROMAGNETIC VALVE.

Specification of Letters Patent. Patented Feb. 20, 1917.

1,216,658.

Application filed January 24, 1916. Serial No. 74,008.

To all whom it may concern:

Be it known that I, LEGENDRE CINQ-MARS, a citizen of the United States, residing at San Francisco, in the county of San Francisco and State of California, have invented certain new and useful Improvements in Electromagnetic Valves; and I do declare the following to be a full, clear, and exact description of the invention, such as will enable others skilled in the art to which it appertains to make and use the same.

This invention relates generally to improvements in electrically operated valves but more particularly to electromagnetically operated valves.

One object of the invention is to provide a means for operating a valve from a point remote from the location of the valve.

A further object of the invention resides in the provision of a device which is simple in construction, durable, efficient and reliable in operation, and well adapted to the purpose for which it is designed.

With these and other objects in view, the invention consists of certain novel features of construction and the combination and arrangement of parts as will be hereinafter more fully described and claimed.

In the accompanying drawings forming a part of the specification, and in which similar reference numerals designate like parts throughout the several views:

Figure 1 is a side elevation of a device constructed in accordance with this invention;

Fig. 2 is a front elevation of the same;

Fig. 3 is a vertical sectional view taken on the line 3—4 of Fig. 1, showing the cores and bell in their lowered positions;

Fig. 4 is a similar view taken on the same line showing the cores in their raised positions;

Fig. 5 is a top plan view of the device;

Fig. 6 is a horizontal sectional view taken on the line 6—6 of Fig. 3;

Fig. 7 is a similar view taken on the line 7—7 of Figs. 1 and 3;

Fig. 8 is a similar view taken on the line 8—8 of Fig. 3;

Fig. 9 is a similar view taken on the line 9—9 of Figs. 1 and 3; and

Fig. 10 is a perspective view of the cores and bell showing these parts disassembled.

The preferred form of the present invention comprises a tubular cast iron casing 1

having a bottom 2 which is provided with a centrally arranged threaded nipple 3 to which is attached a gas or other fluid inlet pipe, not shown. Extending upwardly from the bottom 2 of the casing 1 is a centrally arranged annular flange 4 which, in connection with the bottom 2 and lower end of the casing 1, forms an annular well 5 in which is placed a suitable liquid, preferably mercury, the purpose of which will hereinafter appear. Access to this mercury well 5 is obtained by removing a screw plug 6 which is disposed in a threaded aperture 7 in the lower end of the casing 1. Extending laterally from one side of the casing 1 is an internally threaded nipple 3', to which is connected one end of a fluid outlet pipe, not shown.

The upper end of the casing 1 is enlarged at 8, by which shoulders 9 are formed on its inner sides, as most clearly shown in Figs. 3 and 6 of the drawings. However, the opposite sides of the casing 1 below its enlarged upper portion 8 is provided with rectangularly shaped guides 10, whose wall 80 is of greater thickness than the main body or enlarged upper portion of the casing, the said wall at the upper end of each guide being reduced in thickness to coincide with that of the casing whereby to form shoulders 11, the purpose of which will be hereinafter described.

Resting upon the shoulders 9 is a fiber washer 12, to the central portion of which is secured in any suitable manner the lower 90 end of a metallic tube 13, preferably of brass. The upper end and central portion of this tube 13 are also provided with similar fiber washers 12. These washers 12 fit snugly within the upper end 8 of the casing 1 and retain the tube 13 spaced from the inner sides thereof, as well as to insulate the solenoids 14 and 15, which are wound upon said tube 13 between said washers 12, from each other and the metal of the casing. Conductors 16 connect the solenoids 14 and 15 with suitable binding posts 17 secured to a circular disk 18 of fiber or other suitable insulating material. This disk 18 is clamped between the upper edges of the casing 1 and the annular flange 19 of a nut member 20, which is threaded to the upper end of said casing 1. If desired, a brass or metal friction ring 21 may be disposed between the upper face of the disk 18 and the lower face 110

of the flange 19 to prevent said disk 19 from becoming injured when said nut member 20 is turned. Additional conductors 22 lead from the binding posts 17 to the batteries 23 and suitable switch members are shown in the form of push buttons 24, whereby the solenoids 14 and 15 are energized independently of each other. The batteries 23 and push buttons 24 form no part of the present invention although some equivalent means for energizing the said solenoids 14 and 15 is necessary.

Slidable within the tube 13 is a cylindrical soft iron core 25 which is substantially equal in length to the length of each of said solenoids 14 and 15, and extending from the lower end of the core 25 is a threaded lug 26 which engages the internally threaded end 27 of a tubular core 28 which is made of a material not attracted by magnetism, preferably brass. This tubular core 28 has the same outside diameter as the core 25 and is arranged in alignment with the latter. Extending in opposite directions from the lower end of the core 28 are tubular arms 29 in which are disposed plungers 30, the latter being projected by coiled springs 31 into the aforesaid rectangular guides 10. The lower end of the core 28 is further provided with a threaded lug 32 which engages an internally threaded aperture 33 arranged in the top of a bell 34, the lower end of which is reduced in thickness from its inner sides and beveled at its lower end as at 35. A suitable rubber washer 36 provided with diametrically opposite ears 37 is clamped between the lower end of the core 28 and the top of the bell 34 to prevent gas from entering the upper portion 8 of the casing 1, and if desired, an additional rubber washer 38 may be inserted into the upper end of the bell 34 to act as a bumper when the latter drops. However, this is a mere matter of expedience, and may be dispensed with if desired.

With the parts in the position shown in Fig. 3 of the drawings, it may be seen that the gas which escapes over the top of the annular flange 4 and downwardly between the outer sides thereof and the inner sides of the bell 34 will be checked by the liquid seal formed by the engagement of said bell with the mercury in the aforesaid well 5. When however, the solenoid 14 is energized by operating the proper push button 24, the core 25 will be drawn upwardly, thereby raising the bell 34 and disengaging its lower end with said mercury in the well 5. The plungers 30, upon being raised above the shoul-

ders 11, spring outwardly and retain the bell raised even after the solenoid 14 is deenergized. Obviously with the parts in the position shown in Fig. 4, the gas may pass under the lower end of the bell and then upwardly and out through the outlet nipple 3'.

To again check the flow of gas, the other button 24 is pushed. This energizes the solenoid 15 which draws the core 25 downwardly, the former being of sufficient strength to cause the plungers 30 to be retracted, and passed below the shoulders 11. The rubber washer or bumper 38 absorbs most of the jar when the bell 34 drops, while the beveled ends of the latter prevent splashing of the mercury. However, if any splash occurs, it is checked by the washer 36 and the bumper 38.

From the foregoing it may be seen that the objects of the invention have been effectively carried out. However, it is to be noted that various minor changes in form and proportion may be resorted to without departing from the spirit of this invention, and hence I do not wish to be limited to the construction herein shown and described other than to the extent to which the appended claim limits me.

I claim as my invention.

In a device of the character described, the combination of an upright tubular casing having its upper end enlarged in diameter, the opposite sides of said casing below its enlarged upper portion being also enlarged to form rectangularly-shaped guides, the wall of said guides being of greater thickness than that of said enlarged upper portion, said wall at the upper end of each guide being reduced in thickness to coincide with that of the latter to form shoulders, a solenoid mounted in said enlarged upper portion, a valve arranged in the lower end of said casing, a magnetic core slidable vertically in said solenoid and actuated by the same, said core being operatively connected with said valve, and spring-pressed plungers carried by said core, said plungers being projected into said guides and adapted to engage said shoulders when said valve is open, whereby to retain it in such position.

In testimony whereof I have hereunto set my hand in presence of two subscribing witnesses.

LEGENDRE CINQ-MARS.
